UNITED STATES PATENT OFFICE.

SANFORD BOUTON DICKINSON, OF BATH, NEW YORK.

ROADWAY.

1,265,628.

Specification of Letters Patent.

Patented May 7, 1918.

Application filed February 7, 1918. Serial No. 215,856.

To all whom it may concern:

Be it known that I, SANFORD B. DICKINSON, a citizen of the United States, and a resident of Bath, in the county of Steuben 5 and State of New York, have invented a new and Improved Roadway, of which the following is a full, clear, and exact description.

This invention relates to roadways, and 10 particularly to built up structure for vehicles of different kinds which will permit excessive use without injury to the roadway or to the vehicles.

Another object in view is to provide a 15 roadbed with spaced metal tracks or ways for certain classes of vehicles, and a central roadway for other vehicles.

A still further object of the invention, more specifically, is the provision of metal 20 tracks for vehicles provided with a drainage structure for drawing off any excess water adjacent the tracks.

In the accompanying drawings:

Figure 1 is a top plan view of a short section 25 of road disclosing an embodiment of the invention.

Fig. 2 is an enlarged fragmentary sectional view through Fig. 1 on line 2—2.

Fig. 3 is a section through Fig. 2 on line 30 3—3, the same being on a slightly enlarged scale.

Fig. 4 is a perspective view of a modified form of plate disclosing certain features of the invention.

Referring to the accompanying drawings by numerals, 1 indicates a roadway made 35 from stone, gravel, or any other desired material prepared in any desired manner for sustaining any weights and for accommodating fast moving vehicles, as for instance automobiles. On each side of the central strip 1 there are provided side vehicle roadways 2 and 3. Each of these roadways consists of tracks 4 and 5 and a central section 40 6. The central section 6 is of any desired material, as for instance, cinders, cracked stone, or a mixture of different materials which will act as a supporting surface. The side roadways 2 and 3 may be used for 45 vehicles of any kind, but are preferably provided for horse drawn vehicles, and the tracks 4 and 5 made of such a width as to accommodate any width wagon, buggy, or other vehicle. The various tracks are made 50 up of a number of track sections 7 of metal, said track sections having a central flat sur-

face with upstanding flanges 8 and 9 on each side, and depending flanges 10 and 11. The upstanding flanges 8 and 9 are intended to prevent, or at least resist, the removal of the wheels of the vehicles from the tracks. The depending flanges are intended to receive the various bolts 12, which not only pass through the flanges, but pass through 60 the metallic posts 13 so as to rigidly secure the plates 7 to the various posts 13. It is of course, evident that the upstanding and depending flanges act as reinforcing means in addition to the use just described. The various posts 13 are hollow and made from 65 sheet metal of any desired kind, preferably steel, said posts being provided with a plurality of perforations 14 on each side at the upper part, said perforations registering with the perforations in the depending 70 flanges 10 and 11 whereby water may freely flow from the pockets 15 and 16. The pockets 15 and 16 are formed by inclosing members 17 and 18 which may be any desired shape, but provided with apertures 19 at 75 the upper part so that any surface water in the central sections 6 of the outer roadways and the central roadway 1 may freely flow through said apertures into the pockets 15 and 16 and from thence into the various 80 posts 13, and through openings 20 in the concrete foundation blocks 20' into the cracked stone 21, from which it passes into the earth, or to a suitable drain pipe, according to the particular construction of the 85 road at any point. Where the elevation or structure of the road naturally sheds the water merely a quantity of cracked stone 21 is all that is necessary to dispose of the excess water, whereas in the low places it 90 may be necessary to connect the cracked stone 21 to the drainage channels or other cracked stone by drainage pipes.

The entire roadway structure may be constructed in any desired manner, or by any 100 desired method, but preferably the roadway is graded and a proper foundation provided for the various posts 13 so that said roadway structure will be substantially in a horizontal plane, in order to reduce to a 105 minimum the necessary power to move vehicles thereover.

In Fig. 4 will be seen a slightly modified form of the invention in which the plate 7 is provided with a central rail 22 and a depressed section 23, said rail being arranged 110 centrally of the plate so as to accommodate

2
trolley cars on the side road structures 2 and 3. Ample space is provided on each side of rail 22 to accommodate the wheels of ordinary vehicles so that the track could be used for the double purpose of ordinary horse drawn or other vehicles and for trolleys, or other vehicles necessitating a track. In order that the plate 7 or 7', especially 7', may properly support the heavy loads 10 designed to be drawn thereover a depending flange 24 is provided by reinforcing the center of the plate, said flange fitting into notches in the posts 13. Also to steady and to make the two tracks a single structure 15 a tie plate 25 is bolted or otherwise rigidly secured to the various posts 13. Preferably there is a tie plate on each side of each post tying the posts together, so that any movement on one track will be communicated to 20 the other.

What I claim is:

1. A roadway structure for unflanged vehicle wheels comprising a central roadway, a side roadway arranged on each side of said central roadway, and a pair of tracks on each of said side roadways, each of said tracks comprising flat metallic wheel receiving plates formed with an upstanding flange on each side, and supporting posts for sustaining said plates and holding the same in alinement.
2. A roadway structure for unflanged vehicle wheels comprising a central roadway, a side roadway on each side of said central roadway, and a track on each of said side roadways, each of said tracks comprising a plurality of flat plates arranged end to end, each of said plates having upstanding flanges on each side for resisting the removal of a wheel therefrom, and a post overlapping the abutting ends of said plates for supporting the plates and at the same time holding the plates in alinement.
3. A roadway structure for unflanged vehicle wheels comprising a central roadway for one type of vehicle, a roadway on each side of said central roadway for different types of vehicles, each of said side roadways comprising supporting plates having up-

standing flanges, a flat face for receiving and holding in place the wheels of vehicles, a post overlapping the abutting ends of said plates, means for securing the abutting ends of said plates to said posts, and a foundation structure for each of said posts. 50

4. A roadway structure comprising spaced roadways having tracks and a central roadway therebetween, each of said tracks comprising a series of independent metallic plates provided with upstanding flanges on each edge and depending flanges on each edge, a post at the abutting ends of each pair of plates, said posts overlapping said abutting ends and in turn being overlapped by said depending flanges, a securing member 65 extending through said flanges of each plate and through the respective posts connecting the plates to said posts whereby the plates for supporting vehicle wheels are carried by the posts while the animals drawing the vehicles may travel said central roadway. 70

5. A roadway structure provided with a pair of metallic tracks formed from a plurality of comparatively wide plates having a flat surface, a hollow post arranged at the abutting ends of the respective plates, means for connecting said plates with said posts, each of said posts having perforations near the top, a perforated guard covering said perforations, and a perforated foundation member for supporting each of said posts whereby the surface water adjacent the tracks may freely drain into and through said posts. 75

6. A roadway structure provided with a pair of metallic tracks, each of said tracks being formed with a plurality of independent plates having flat plates having upstanding flanges on each edge, each of said plates being provided with a rail member 90 arranged substantially centrally and extending longitudinally of the plate, whereby a trolley car may use said tracks, and ordinary vehicles may use said tracks, and means for simultaneously supporting said plates 95 and holding same in alinement.

SANFORD BOUTON DICKINSON.
